Specification of Letters Patent.

Patented July 14, 1914.

Application filed June 7, 1913. Serial No. 772,278.

To all whom it may concern:

Be it known that I, HARVEY CONOVER, a citizen of the United States, and a resident of Evanston, in the county of Cook and State of Illinois, have invented certain new and useful Improvements in Boxes; and I, HARVEY CONOVER, do hereby declare that the following is a full, clear, and exact description thereof, reference being had to the accompanying drawings, and to the letters of reference marked thereon, which form a part of this specification.

This invention relates to improvements in boxes more particularly intended to contain cigarettes and consists of the matters hereinafter described and more particularly pointed out in the appended claims.

Cigarettes are usually packed in paste-board boxes which are of a width equal to the length of the cigarette and are of a depth equal to one or two diameters of the cigarette, depending upon whether the box is to contain one or two layers of cigarettes. The cigarettes are packed in the box comparatively close together so as to provide a minimum length of box for the maximum number that the box is designed to contain, in order that the box may be conveniently carried in the pocket of the smoker. With the cigarettes packed in this way, it is somewhat difficult to grasp a single cigarette to withdraw it from the box, after the lid is opened, particularly in the case of the first cigarette to be taken from the box when the layer is complete and all the cigarettes are tightly packed together. Cigarette smokers are familiar with the fumbling about with thumb and finger that occurs when the carrier of the box attempts to remove a cigarette, or when one to whom he offers his box attempts to remove a cigarette.

The object of my invention is to provide a box containing an auxiliary holder for the layer or layers of cigarettes which, in the opening of the box, may be brought into such position that any one of the cigarettes in the layer or layers may be grasped by one end and withdrawn without disturbing the other cigarettes in the layer, just as a cigar or cigarette may be withdrawn from the regular cigar or cigarette case.

The advantages of my invention will appear as I proceed with my specification.

In the drawings: Figure 1 is a perspective view of my improved cigarette box with

part of the cover broken away to show the auxiliary container or holder within the box and the cigarettes therein. Fig. 2 is a perspective view illustrating the appearance of the box when opened up in order to remove one or more of the cigarettes. Fig. 3 is a view representing a vertical section of the box shown in Fig. 1 in a plane indicated by the line 3—3 of Fig. 1. Fig. 4 is a view representing a vertical section through the box shown in Fig. 1 in a plane indicated by the line 4—4 of Fig. 1.

Referring now to that embodiment of my invention shown in the drawings, in which I have illustrated a box adapted to contain a single layer of cigarettes, 10 indicates the box as a whole and 11 indicates the inner auxiliary container or holder for the layer of cigarettes. The box 10 as shown is of any familiar set-up box construction and comprises a body member 12 and a lid member 13, which divide the box on a median plane between the top and bottom thereof.

12^a, 12^b and 12^c indicate respectively the ends and one side of the body of the box and 13^a, 13^b and 13^c like parts of the lid section of the box.

14 indicates the side of the box at the hinge which is common to both the body and lid sections of the box, each of which is hinged to swing upon one of the lateral edges of said side 14.

The container 11 preferably comprises side members 15, 16, end members 17, 17, and the bottom member 18. The sides 15 and 16 are of a depth less than the cigarettes so as to leave the upper end parts of the cigarettes contained in the holder fully exposed on each side so as to be grasped by the thumb and finger in order to be conveniently withdrawn from the container. The side 16 and the ends 17 are fixed to the bottom wall 18 of the container, while the side 15 has a hinged connection to the bottom wall 18 of the container and the two walls 15 and 16 are preferably connected together at or near their upper edges by means of an elastic member 19, which as shown consists of a band of india rubber, knotted at its ends and engaged in slots or cuts 20, 20 in the side walls 15 and 16. By this construction the sides 15 and 16 of the container are caused to yieldingly engage against the layer of cigarettes and hold them in position, even

after one or more of the cigarettes have been withdrawn, without in any way interfering with the ease with which the cigarettes may be withdrawn one by one as desired.

The operation of my improved box is apparent from the above description. When the box is closed the container lies flat and inclosed between the top and bottom sections of the box, as illustrated in Fig. 1. When it is desired to remove one or more cigarettes from the box, the cover or lid 13 is swung open in the usual manner and at the same time the container itself is caused to swing into a position substantially as illustrated in Fig. 2. After the desired number of cigarettes are withdrawn, the lid is swung toward closed position, this movement bringing the container into its closed position and the movement being continued, the box is closed in the usual manner.

While in describing one embodiment of my invention, I have referred to certain details of mechanical construction and arrangement, it is understood that my invention is in no way to be limited thereby, except as pointed out in the appended claims.

I claim as my invention:—

1. A box of the character described, comprising a body section, a lid section, an intermediate side wall section common to both body and lid sections, said body and lid sections being hinged to the opposite edges of said intermediate side wall section and a holder comprising side walls, end walls and a bottom wall, said holder being fixed to said intermediate section, and the side walls of said holder being of less width than the width of the box.

2. A box of the character described, comprising a body section, a lid section, an intermediate side wall section common to both said body and lid sections, said body and lid sections being hinged to the opposite lateral edges of said side wall section, and a container or holder fixed to said intermediate side wall section and adapted to lie within the box when closed, said container having oppositely disposed side walls, which are of substantially less width than the width of the box, and yielding means connecting the side walls of said container.

3. A box of the character described, comprising a body section, a lid section, an intermediate side wall section common to both the body and lid sections, said body and lid sections being hinged to the opposite lateral edges of said intermediate side wall section, and a container fixed to said intermediate side wall section of the box, said container comprising oppositely placed side walls and oppositely placed end walls, one of the side walls of the container being fixed to the end walls thereof, and the other side wall comprising a loose flap hinged to swing with respect to the intermediate side wall section of the box, and yielding means connecting said loose flap with the opposite side wall of the container.

In testimony, that I claim the foregoing as my invention I affix my signature in the presence of two witnesses, this 13th day of May A. D. 1913.

HARVEY CONOVER.
